HAND HELD AIR BLOWER

Paul D. La Gorce, Oakland, Calif., assignor to Gordon G. Hughes, San Anselmo, Calif.

Filed Nov. 23, 1971, Ser. No. 201,606

Term of patent 14 years

Int. Cl. D23—99; D15—05
U.S. Cl. D23—162

FIG. 1 is a view in perspective of a hand held air blower showing the features of my new design;

FIG. 2 is a rear view in elevation of the same;

FIG. 3 is a top view of the same; and

FIG. 4 is a right side view in elevation of the same which is substantially the same as the left side view in elevation.

The electric cord is shown in broken lines in FIGS. 2, 3 and 4 for illustrative purposes only.

I claim:

The ornamental design for a hand held air blower, substantially as shown and described.
